UNITED STATES PATENT OFFICE

FRANK P. GALLIPOLI, OF ENGLEWOOD, NEW JERSEY

DEVICE FOR PRODUCING AND DISPENSING LATHER

Application filed April 23, 1930. Serial No. 446,605.

This invention relates to devices for producing and dispensing a liquid or semi-liquid composition, such as soap lather, and is in the nature of an improvement upon my prior United States Letters Patent No. 1,489,999 and upon a copending application, Serial No. 369,873, filed jointly by me and another.

The present invention broadly aims to generally improve the structure of the previous devices above mentioned, in order to render the same more practical commercially.

The invention seeks for one of its objects to provide means for agitating the soap and water contained in the device to produce the lather without the necessity of bodily shaking the same, as was previously required.

The present invention further contemplates the use of the agitating means as a stop for limiting the inward movement of the dispensing plunger, whereby to preclude any possibility of discharging the water contained in the device and to insure the dispensing of the lather only.

The invention further comprehends an improved device of this character which is less expensive and more practical to produce and assemble, which is simpler in its construction and mode of use, which is more efficient in its purpose and more attractive in its appearance.

With the above recited and other objects in view, reference is had to the following description and accompanying drawings, in which there is exhibited one example or embodiment of the invention, while the claims define the actual scope of the same.

In the drawings:

Figure 1 is a perspective view of the device.

Figure 2 is a vertical enlarged sectional view therethrough.

Figure 3 is a horizontal sectional view through the device taken approximately on the line indicated at 3—3 in Figure 2.

Referring to the drawings by characters of reference, 5 designates a cylindrical container body which is provided at its upper end with an annular inwardly extending shoulder 6. A bottom 7 is removably associated with the lower end of the body 5, and said

bottom includes inner and outer spaced concentric upstanding walls 8 and 9, the latter wall 9 being of a size to telescopically fit over the lower end of the body 5. The means for detachably holding the bottom in associated relation with the body 5 preferably consists of one or more bayonet slots 10 and pins 11, in which the upper walls 12 of the bayonet slots are inclined so as to impinge and clamp a gasket 13 between the bottom 7 and the lower edge of the container body 5 when the bottom and body are fully interengaged. The inner wall 8 of the bottom structure is provided with a top 14 which is designed to accommodate a suitable heater H when the device is rested on a heater casing C.

As in the prior patent and application referred to, the device includes an axially movable plunger 15 having a depending marginal wall 16, and the plunger is provided with an eccentric aperture 17 to receive a discharge spout 18 which is removably associated with the apertured portion, and which discharge spout communicates with the interior of the container body through the plunger 15. In the present instance, means is provided and concealed within the container body for normally moving the plunger upward and for tensioning the same against downward movement, and, as illustrated, said means is in the nature of a coiled expansion spring 19, the upper end convolution of which seats within a groove 20 in the lower edge of the marginal flange 16, and the lower end convolution of which seats against an annular inwardly projecting bead 21 at the lower free end of the container body, and which bead serves in the capacity of a plunger spring retaining seat over which the lower end convolution of the plunger spring 19 is forced, it being understood that the lower end convolution of the spring is of slightly greater normal diameter than the remaining convolutions, so that it must be initially contracted radially to pass through the restricted lower end of the container body where it subsequently expands radially above and behind the bead 21.

In order to provide means for depressing the plunger against the action of the plunger

spring 19, a plunger shaft 22 is connected with and carried by the plunger, preferably at the axial center thereof, and extends upwardly therefrom and is provided at its upper end with a head 23 having diametrically oppositely projecting manipulating handles or finger rests 24. The plunger shaft is preferably in the nature of a tube or hollow cylindrical shaft section which is formed with an exterior thread 25 at its lower end which threadedly engages within a threaded recess 26 in the plunger 15. The recess is further provided with a bottom wall or flange 27 having a central bearing aperture 28 of reduced diameter with respect to the internal diameter of the tubular shaft 22, and the head 23 at the upper end of the plunger shaft is also formed with a reduced bearing opening 29 of approximately the same size as the bearing opening 28.

A reciprocatory agitator also forms a part of the present invention, and said agitator includes a shaft 30 which extends axially through the plunger shaft 22 and the bearing openings 28 and 29, and which plunger shaft is provided intermediate its ends with a collar 31 constituting a spring seat against which the upper end convolution of a spring 32 seats. The spring 32 surrounds the agitator shaft 30, is located within the plunger shaft 22 and has its lower end convolution seated against the bottom wall or flange 27 of the recess 26 of the plunger and functions to normally move the plunger shaft 30 upwardly until the collar 31 contacts with a suitable packing material 33 positioned within the upper end of the plunger shaft 22 between its head 23 and the collar 31. The lower end of the agitator shaft 30 carries an agitator head or element 34 having suitable radial blades 35, and which agitator head or element 34 is assembled and maintained in place on the lower reduced threaded end 36 of the agitator shaft and against the shoulder 37 by means of a retaining nut 38. The upper end of the agitator shaft is provided with a manipulator head or button 39.

In use and operation, water W is introduced into the container body 5 to approximately the level indicated in the drawings, preferably through the eccentric aperture 17 of the plunger after removal of the discharge spout. Soap, either in liquid, cake, cream or any other form, is also introduced into the receptacle body 5, and the discharge spout 18 replaced. The lather is produced by rapidly and successively pressing downwardly on the manipulator head 39 of the agitator shaft and permitting the spring 32 to project the agitator shaft and agitator head upwardly. This obviously agitates the water and soap and produces a quantity of lather which obviously flows upon or is buoyed up by the water so that the lather is arranged in the upper portion of the receptacle body 5. The

lather is then dispensed by depressing the plunger 15 by engaging the fingers over the manipulating handles or finger rests 24 provided on the head 23 at the upper end of the plunger shaft 22, the downward movement of the plunger functioning to express the desired quantity of lather from the receptacle body 5 through the discharge spout onto the hand of the barber or user, whereby it may be applied by the hand in lieu of using a shaving brush. The downward movement of the plunger is arrested or limited by contact of the lower end 36 of the agitator shaft with the top 14 of the inner wall 8 of the bottom structure, as it will be clearly understood that the downward thrust of the plunger will be impinged upon the packing 33, engaging with the collar 31. Due to the fact that the packing 33 is necessarily slightly yieldable, the shock of the contact of the end 36 of the agitator shaft will be cushioned.

From the foregoing construction, it is also apparent that the device may be readily and easily assembled without the necessity of employing any special tools or the services of expert mechanics. The assembly of the parts is accomplished in approximately the following manner: The upper end of the agitator shaft with the manipulator head or button removed is inserted through the lower end of the plunger shaft 22 after the packing has been initially introduced into the plunger shaft and the manipulator head or button 39 is then attached; next, the spring 32 is engaged over the projecting lower end of the agitator shaft 30 and inserted into the plunger shaft 22 until its upper end convolution engages the spring seat or collar 31; the lower end of the agitator shaft is next inserted through the bearing opening 28 in the bottom wall or flange 27 of the plunger 15 and the exteriorly threaded lower end 25 of the plunger shaft is then threadedly engaged within the internally threaded recess 26; the agitator head 34 is then positioned over the reduced threaded lower end 36 of the agitator shaft into engagement with the shoulder 37, and the nut 38 is applied to clamp the agitator head in place. The plunger 15 with the parts thus assembled is now inserted through the lower end of the receptacle body 5 with the plunger and agitator shafts 22 and 30 projecting upwardly. The plunger spring 19 is next inserted and its upper convolution automatically seats within the groove 20 at the lower edge of the marginal flange 16 of the plunger, while the lower end convolution of the spring is snapped beyond and over the annular inwardly projecting bead 21 at the lower free end of the container body. The bottom 7 is then applied as previously explained, and the dispensing or discharge spout 18 is next connected with the apertured portion 17 of the plunger so that the device is ready for use. It will thus be seen that

the facility with which the device may be assembled or disassembled makes for the ease with which the device may be cleansed and sterilized to maintain it in a highly sanitary condition.

5 While the device has been described and is particularly designed as a means for producing and dispensing soap lather, it is to be clearly understood that the same may be employed for mixing and dispensing liquid or semi-liquid compositions embodying any ingredients.

10 While there has been illustrated a preferred form of the invention, it is to be understood that no restriction is intended to the precise structural details, and that variations and modifications which properly fall within the scope of the claims may be resorted to when found desirable.

15 20 What is claimed is:

1. In a device for mixing and dispensing fluid substances, a container body for receiving the ingredients to be mixed and dispensed, a plunger having a discharge spout through 25 which the contents are expressed by downward movement of the plunger in the container body, means within the container body for normally moving the plunger upward and for tensioning the same against downward movement and means extending downwardly through the plunger and movable relatively thereto for agitating the contents to produce the fluid mixture to be dispensed.

30 35 2. In a device for mixing and dispensing fluid substances, a container body for receiving the ingredients to be mixed and dispensed, a plunger having a discharge spout through which the contents are expressed by downward movement of the plunger in the container body, means within the container body for normally moving the plunger upward and for tensioning the same against downward movement, means extending downwardly through the plunger and movable relatively thereto for agitating the contents to produce the fluid mixture to be dispensed and means for moving the agitator means upwardly to a normal position and for tensioning the same against downward movement.

40 45 50 55 60 65 3. In a device for mixing and dispensing fluid substances, a container body for receiving the ingredients to be mixed and dispensed, a plunger having a discharge spout through which the contents are expressed by downward movement of the plunger in the container body, means within the container body for normally moving the plunger upward and for tensioning the same against downward movement, means extending downwardly through the plunger and movable relatively thereto for agitating the contents to produce the fluid mixture to be dispensed, means for moving the agitator means upwardly to a normal position and for tensioning the same against downward movement

and stop means for limiting the upward movement of the agitator means and for disposing the same in its normal uppermost position.

4. In a device for mixing and dispensing fluid substances, a container body for receiving the ingredients to be mixed and dispensed, a plunger having a discharge spout through which the contents are expressed by downward movement of the plunger in the container body, means within the container body for normally moving the plunger upward and for tensioning the same against downward movement, means extending downwardly through the plunger and movable relatively thereto for agitating the contents to produce the fluid mixture to be dispensed, means for moving the agitator means upwardly to a normal position and for tensioning the same against downward movement and stop means for limiting the upward movement of the agitator means and for disposing the same in its normal uppermost position, said agitator means serving when in its normal position to act as a means for limiting the downward movement of the plunger to a predetermined point disposed above its bottom.

5. In a device for producing and dispensing soap lather, a container body for receiving soap and water, a plunger having a discharge spout through which the lather is expressed and dispensed by downward movement of the plunger in the container, means within the container body for normally moving the plunger upwardly and for tensioning the same against downward movement and means extending downwardly through the plunger and movable relatively thereto for agitating the soap and water to produce lather within the upper end of the container body above the water level.

6. In a device for producing and dispensing soap lather, a container body for receiving soap and water, a plunger having a discharge spout through which the lather is expressed and dispensed by downward movement of the plunger in the container, means within the container body for normally moving the plunger upwardly and for tensioning the same against downward movement and means extending downwardly through the plunger and movable relatively thereto for agitating the soap and water to produce lather within the upper end of the container body above the water level, said means also serving to limit the downward movement of the plunger to a point disposed above the maximum water level in the container body whereby to prevent discharge of the water and allow for the dispensing of lather only.

7. In a device for producing and dispensing soap lather, a container body for receiving soap and water, a plunger having a discharge spout through which the lather is expressed and dispensed by downward move-

ment of the plunger in the container, a coiled expansion spring positioned within the contained body and interposed between the lower end of the plunger and the bottom of the container body for normally effecting upward movement of the plunger and for tensioning the same against downward movement, a tubular plunger shaft extending upwardly from the plunger having manipulating means at its upper end, an agitator shaft extending through the plunger and plunger shaft having an agitator head at its lower end and a manipulating head at its upper end.

8. In a device for producing and dispensing soap lather, a container body for receiving soap and water, a plunger having a discharge spout through which the lather is expressed and dispensed by downward movement of the plunger in the container, a coiled expansion spring positioned within the container body and interposed between the lower end of the plunger and the bottom of the container body for normally effecting upward movement of the plunger and for tensioning the same against downward movement, a tubular plunger shaft extending upwardly from the plunger having manipulating means at its upper end, an agitator shaft extending through the plunger and plunger shaft having an agitator head at its lower end and a manipulating head at its upper end, a coiled contractile spring within the plunger shaft surrounding the agitator shaft and coacting respectively with the agitator shaft and plunger for normally moving the agitator shaft upwardly and for tensioning the same against downward movement and coacting stop means provided respectively on the plunger and agitator shafts for limiting the upward movement of the agitator shaft against the action of the agitator shaft spring, said agitator shaft further serving in its uppermost limited position, as means for limiting the downward movement of the plunger.

9. In a device for producing and dispensing soap lather, a container body for receiving soap and water, a plunger having a discharge spout through which the lather is expressed and dispensed by downward movement of the plunger in the container, a coiled expansion spring positioned within the container body and interposed between the lower end of the plunger and the bottom of the container body for normally effecting upward movement of the plunger and for tensioning the same against downward movement, a tubular plunger shaft extending upwardly from the plunger having manipulating means at its upper end, an agitator shaft extending through the plunger and plunger shaft having an agitator head at its lower end and a manipulating head at its upper end, a coiled contractile spring within the plunger shaft surrounding the agitator shaft and coacting respectively with the agitator shaft and plunger for normally moving the agitator shaft upwardly and for tensioning the same against downward movement and coacting stop means provided respectively on the plunger and agitator shafts for limiting the upward movement of the agitator shaft

against the action of the agitator shaft spring.

10. In a device for producing and dispensing soap lather, a container body for receiving soap and water, a plunger having a discharge spout through which the lather is expressed and dispensed by downward movement of the plunger in the container, a coiled expansion spring positioned within the container body and interposed between the lower end of the plunger and the bottom of the container body for normally effecting upward movement of the plunger and for tensioning the same against downward movement, a tubular plunger shaft extending upwardly from the plunger having manipulating means at its upper end, an agitator shaft extending through the plunger and plunger shaft having an agitator head at its lower end and a manipulating head at its upper end, a coiled contractile spring within the plunger shaft surrounding the agitator shaft and coacting respectively with the agitator shaft and plunger for normally moving the agitator shaft upwardly and for tensioning the same against downward movement and coacting stop means provided respectively on the plunger and agitator shafts for limiting the upward movement of the agitator shaft against the action of the agitator shaft spring, said agitator shaft further serving in its uppermost limited position, as means for limiting the downward movement of the plunger.
